(57) **CLAIM**

I claim the ornamental design for a dispensing head, as shown and described.

DESCRIPTION

FIG. 1 is a perspective view of a dispensing head showing our new design;

FIG. 2 is a side view of the dispensing head shown in FIG. 1;

FIG. 3 is a side view of the dispensing head shown in FIG. 1;

FIG. 4 is a front view of the dispensing head shown in FIG. 1;

FIG. 5 is a rear view of the dispensing head shown in FIG. 1;

FIG. 6 is a top view of the dispensing head shown in FIG. 1; and,

FIG. 7 is a bottom view of the dispensing head shown in FIG. 1.

The broken lines in the drawings depict environmental subject matter only and form no part of the claimed design.
